UNITED STATES PATENT OFFICE

2,401,419

IMPULSE DISTRIBUTOR

Eugene A. Ford, Scarsdale, N. Y., assignor to International Business Machines Corporation, New York, N. Y., a corporation of New York

Original application April 15, 1942, Serial No. 439,016. Divided and this application May 18, 1943, Serial No. 487,445

1 Claim. (Cl. 200—26)

1

This invention relates to impulse distributors. One object of the invention is to provide an impulse distributor capable of reliable operation at high speed.

Another object is to provide an impulse distributor having a construction which facilitates assembly and repair.

Another object is to provide an impulse distributor which can be accurately timed, both as to the start and stop time in the cycle, and the length of the impulse.

Other objects of the invention will be pointed out in the following description and claims and illustrated in the accompanying drawings, which disclose, by way of example, the principle of the invention and the best mode, which has been contemplated of applying that principle.

The present application is a division of my copending application Serial No. 439,016, filed April 15, 1942, for a Distributor system.

In the drawings:

Fig. 1 is a plan view, partly in section, of the distributor.

Fig. 2 is a partial sectional view on an enlarged scale, illustrating the mounting of the contact inserts in the disks.

Fig. 3 is a sectional view, taken on line 3—3 of Fig. 1, and illustrating the coaction between a brush contact and a distributor contact insert.

Fig. 4 is a sectional view on an enlarged scale taken on line 4—4 of Fig. 1, and illustrating the construction and assembly of the pair of disks comprising the novel distributor.

Fig. 5 is a timing diagram of the pair of distributor disks.

Fig. 6 is a simplified circuit diagram illustrating an application of the distributor.

Referring to the drawings and more particularly to Figs. 1, 2 and 4, the distributor comprises a pair of steel disks 10 and 11, mounted on a vertical shaft 12 for rotation thereby. A gear 13 (Fig. 4) is keyed to the shaft 12 and is maintained in position, axially of shaft 12, by projections 13a on the gear interengaging with a slot in the shaft and by a nut 14 threaded to shaft 12. The gear 13 may be driven by any desired means. The end 12a of shaft 12 has its center bored as indicated in Fig. 4, and is split by the slot 12b so as to provide a slightly tapered, compressible and expandable end. Mounted on the tapered end 12a is a laminated Bakelite insulating sleeve 15 having a projecting lip portion 15a interengaging with a groove 12c formed circumferentially of shaft 12. A screw 16 is inserted in the axial bore of shaft 12, which bore is provided with a threaded por-

tion 12d to receive the screw. As the latter is screwed into position, the portion 12a of the shaft is expanded to hold the insulation sleeve 15 firmly in place on the shaft 12.

5 A split steel washer 17 is mounted on the sleeve 15, as shown in Fig. 4, and the disk 11 is mounted on bushing 17 and firmly attached thereto by means of set screws 18 (Figs. 1 and 4) inserted into tapped holes 11a extending radially of the disk. By loosening the set screws 18, the disk 11 can be rotatably adjusted with respect to shaft 12, for purposes as described presently. Also mounted on the sleeve 15, but separated vertically from the bushing 17, is another split steel 10 bushing 17a, upon which the disk 10 is mounted and secured by set screws 18. A brass ring 19 provided with a pin 19a rests freely on the disk 10. A beryllium copper strip 20 (Figs. 1 and 4) 15 constitutes a brush for conducting electrical energy to the disk 10. The brush comprises a pair of curved fingers sitting on the top of the brass ring 19, and a notch 20a cut in the main portion of the brush embraces the pin 19a, to hold the ring against rotation as the disk 10 rotates. During 20 such rotation of the disk 10, the ring 19 floats upon this disk and serves as a sliding contact to conduct electricity to the distributor disk 10. Brush 20 is mounted in any desired manner to the frame of the distributor and a conductor 21 25 supplies current to the brush 20.

30 A series of slots 22 (Figs. 1 and 2) are cut in the periphery of each of the disks 10 and 11. In each slot is mounted a contact insert 23 provided with a groove 23a (Fig. 2) extending for a portion of the length of the insert. A tapped opening 24 is provided in the disks, adjacent each slot, and a screw 25 is threaded into the tapped opening until its head abuts the bottom of the slot 23a, to firmly hold the contact insert in place.

35 The inserts can be easily removed by unscrewing the associated screw 25. Each contact insert comprises a steel portion, cut away adjacent its outer end, into which cutaway section is welded a piece of tungsten, to thereby provide for both better wear and better electrical contact with the cooperating brush.

40 A cooperating brush 26 is provided for each of the disks 10 and 11. Each brush (Fig. 1) comprises a steel rectangular contact carrier 27, both carriers being mounted for angular adjustment about a pivot 28 carried by the insulation mounting block 29, attached in any desired manner to the distributor frame. Current is supplied to each contact carrier 27 by means of a conductor 25 45 30 held in place by a terminal screw 31 connected

to the carrier 27. A lock screw 32 is provided to hold the carrier 27 in an adjusted angular position. An adjusting screw 33 is provided for each carrier, which, when the lock screw 32 is loosened, can be screwed into and out of the carrier 27 to thereby rock the carrier about its pivot 28 to adjust the position of the respective carrier, which is thereupon locked in position by the lock screw 32. A generally U-shaped contact 34 of small mass is pivotally mounted on a pivot member 34a carried by the reduced free end 27a of carrier 27. A leaf spring comprising a long flat spring 35 and a short flat spring 36 is held by a screw 37 to the carrier 27, in position for the long spring to engage a projecting end 34b of contact 34, to bias the oppositely projecting end 34c towards the contact inserts 23 of the related disk. A contact stop 34d is riveted to the free end of carrier 27 and limits the rotative movement of the contact 34 towards its cooperating disk. By loosening the lock screw 32 and adjusting the screw 33, as previously described, the angular position of carrier 27 is adjusted to thereby produce a very accurate adjustment between the contact 34 and its cooperating contact inserts 23. Each contact 34, for the respective disks 10 and 11, can be independently adjusted.

The operation and adjustment of the distributor will be explained by reference to Figs. 5 and 6. A contact 23 on the upper disk 10 engages a brush 34 at the time *a* in Fig. 5, completing a circuit from the positive line through an electromagnet 38, wire 21, brush 20, ring 19, disk 10, contacts 23 and 34, and wire 35 to the negative line, energizing the magnet 38. At the time *b*, contact 23 on the disk 11 engages the brush 34, preparing a parallel circuit from the magnet 38 to the negative line through the brush 11, disk 11, contacts 23 and 34, wire 37, condenser 43 and resistance 44 in parallel, and wire 40. The potential on both plates of the condenser being substantially the same, because the resistance of the branch through disk 10 is negligible, the condenser remains uncharged. At the time *c*, the first circuit is broken by disengagement of the contact 23 on the disk 10 from its brush 34. The condenser 43 immediately begins to charge and builds up to a potential close to the potential difference between the positive and negative lines, while the current through the electromagnet diminishes to a low point. At *d*, the contacts 23 and 34 of the disk 11 break. The timing, determined by the values of the condenser 43 and

resistance 44 is such that the break occurs when the current reaches its minimum value, whereby the arcing at the points 23 and 34 is negligible.

Various adjustments can be made to control the time of make and break of the contacts on the disks 10 and 11. The disks can be individually adjusted on the bushings 17 and 11a, to change their relative angular positions and their angular positions in relation to the shaft. The contact holders 27 can be adjusted by means of the screw 33, on releasing the lock screw 32, to change the length of time during which the contact is made between the elements 23 and 34. Due to the sloping end of the contact inserts 23, outward movement of the contact holder 27 will reduce the time of engagement. The distributor therefore has completed flexibility of adjustment of all time factors.

While there have been shown and described 20 and pointed out the fundamental novel features of the invention as applied to a preferred embodiment, it will be understood that various omissions and substitutions and changes in the form and details of the device illustrated and in its 25 operation may be made by those skilled in the art, without departing from the spirit of the invention. It is the intention, therefore, to be limited only as indicated by the scope of the following claim.

30 What is claimed is:

An electrical circuit breaker comprising a single electrical contact element of small mass, and one or more cam contact elements movable in a prescribed path, so as to make and break contact 35 with said single contact element, a supporting arm on which said single contact element is pivotally mounted on a pivot close to the path of said cam contact elements, a spring tending to rotate said single contact element on its pivot toward 40 the path of said cam contact elements, a stop on said supporting arm limiting the rotary movement of said single contact element by said spring, a frame member, and adjustable means mounting said supporting arm to said frame member 45 whereby the angular position of said supporting arm can be adjusted to alter the proximity of said single contact element to the path of said cam contact elements, the contact surfaces of said cam contact elements being inclined to their path of movement so that adjustment of said supporting arm changes the time of contact.

EUGENE A. FORD.
